UNITED STATES PATENT OFFICE.

HOWARD EARL HOOVER, OF CHICAGO, ILLINOIS, ASSIGNOR, BY MESNE ASSIGNMENTS,
TO THE HOOVER COMPANY, OF NORTH CANTON, OHIO, A CORPORATION OF OHIO.

ELECTRIC SUCTION CLEANER.

Application filed February 24, 1921. Serial No. 447,589.

To all whom it may concern:

Be it known that I, HOWARD EARL HOOVER, a citizen of the United States, residing at Chicago, in the county of Cook and State of Illinois, have invented a certain new and useful Improvement in Electric Suction Cleaners, of which the following is a specification.

My invention relates to electric suction cleaners, particularly such as contain in connection with the nozzle a brush and a motor adapted to rotate the brush, and guard fingers, and my invention particularly relates to the guard fingers. It forms in part a continuation of my pending United States applications Serial Number 185,201, filed August 8, 1917, and Ser. No. 265,350 filed Dec. 5, 1918.

In such a machine it is desirable that the brush should pick up and throw into the suction chamber toward the fan the surface litter such as hair, threads, ravelings and the like, and it is desirable that such litter should not adhere to or remain in or on the brush. The fingers are necessary to keep the floor covering from being drawn too far into the suction chamber. Such guard fingers are, however, likely to have various objections. If they are short they not infrequently catch on the loops or threads which form part of the floor covering and which are drawn up into the suction chamber by the movement of air, which is due to the fact that the machine is being moved back and forth by the operator during the operation of sucking up the dust laden air. Such fingers may also if they are too long or project too far into the suction chamber tend to arrest or aid in the arrest of the inwardly moving litter of the class referred to which may tend to fall out of the stream of air with which it is moving upon the inner lower wall of the casing adjacent the ends of the brush fingers. The fingers, if not properly shaped will not sufficiently aid in preventing the adhesion of such surface litter to the brush. The fingers should preferably be of such length as to deliver the litter in question into the stream of dust and litter laden air and at exactly the point where that delivery is made the brush should sweep the ends of the fingers so as to free such material from the brush and fingers to facilitate its delivery into the air stream.

If the arrangement were such that the brush

occasionally reversed its motion then the fingers should be projected above this air stream so as to prevent the catching of threads and loops from the floor covering over the ends of such fingers. 60

Without reference to the direction of the rotation of the brush it might be desirable with certain materials and under certain conditions to extend the fingers above the air stream in which event they will be so long and extend so far into the suction chamber that they could not well engage the loops and threads of the floor covering. Under all these conditions the best possible arrangement of the fingers is that their ends 70 are swept by the brush.

The object of my invention therefore is to associate such brush with fingers in such way as to facilitate the clearing of the brush and the delivery of all such litter from the fingers to the air stream, and for the prevention of the entanglement of the ends of the fingers with the loops, threads and other such loose pieces of the floor covering as may be drawn up into the suction chamber by 80 the action of the air stream. Another object of my invention is to provide U-shaped fingers and means for properly connecting them. 75

My invention is illustrated more or less 85 diagrammatically in the accompanying drawings wherein:

Figure 1 is a part vertical section and part side elevation of a suction cleaner containing my invention. 90

Figure 2 is a detailed view showing the arrangement of the U-shaped fingers.

Figure 3 is a detail of one means of attaching them.

Like parts are indicated by like characters throughout all the drawings. 95

A is a suction sweeper casing having mounted and secured to it, a motor casing B. C is a handle bail pivoted to the sweeper casing and having in its upper end, the handle shaft C'. C² is a handle bail stop adapted when in the position shown in full lines to permit oscillation of the handle between the position indicated at "X" and the position indicated at "Y". When the handle bail stop is pressed forward in opposition to the spring C³, the handle may be moved into the position indicated at "Z". The details of this structure form no part of the present invention and are not described in great de- 110

tail. The suction sweeper casing has the forwardly and downwardly extending open suction mouth D across which are fixed the guard fingers D'. They may be mounted 8 therein in any suitable manner as for example in the frame D² which may or may not be removable from the suction sweeper casing or they may be shaped in joined U-shaped pairs as shown in Figures 2 and 3 10 and may be positioned in the suction sweeper by being inserted through perforations D³ in the wall of the casing. When so mounted, they are secured in position by means of the screws D⁴. The side of the U-shaped member may or may not be flattened as at D⁵ for better engagement with the screw D⁴.

In all forms, the fingers are substantially concentric with the path of the brush and are so positioned as to be swept from end to 20 end by the bristles during each revolution of the brush, the brush revolving in the direction of the free ends of the fingers so as to brush off the fingers anything which may have become lodged thereon. In the form 25 shown in full lines in Figure 1 the guard fingers are curved concentric with the path of the brush and extend toward but are short of the rear wall of the suction nozzle mouth D. The fingers may, however, be made 30 longer as indicated in dotted lines in Figure 1 by the characters E and F. In these forms, the fingers are extended upward and out of the path of the dust laden current of air so that it is practically impossible for anything 35 to become entangled with or caught upon the fingers. All of these three forms are similar in that they are all concentric with the path of the bristles and are all swept by the bristles, and in each of them the end 40 of the guard fingers is out of contact with the rear wall of the suction nozzle. Within the sweeper casing and protruding partially through the opening D is the brush G which is formed of a hollow brush body in which 45 are located a series of bristle bunches G'. The brush itself is mounted for rotation about the stationary shaft G² and carries upon its exterior a belt pulley G³ adapted to be driven by the belt G⁴ which in turn is 50 driven by the driving pulley G⁵ on the lower extension of the motor shaft H. The brush is mounted adjustably in the mechanism I, which forms no part of the present invention and will not here be described in detail. 55 The casing is mounted on the wheels J which are of such height that they hold the nozzle of the casing above the floor. At the rear of the casing, is mounted a pair of wheels J' which are adjustable in height so that the 60 nozzle of the casing may be raised and lowered with relation to the floor by means of the adjustment of the wheels J'.

In operation, the suction of the machine 65 draws the carpet K off the floor and up against and partially into the nozzle in the

manner shown in Figure 1. The current of dust laden air leaves the carpet and in response to the suction generated by the fan L which is mounted on the motor shaft H, 70 pursues a course corresponding to that indicated by arrows in Figure 1. Thus the dust laden air is drawn from the rug into the nozzle, passes through the fan chamber L' and out through the discharge conduit L² 75 where it may be received by any suitable receptacle.

The use and operation of my invention are as follows:

In the suction cleaners of the class here 80 illustrated, as they are ordinarily made, there is found a motor and a rotary brush driven by the motor at a relatively high rate of speed normally continuously in the same direction. This brush sweeps up and carries into the machine the litter, hair, threads, and the like which may be on the floor. The cleaner preferably has a relatively wide nozzle or inlet and the carpet responsive to the action of the suction of the current of air passing through the machine rises to the lips of the nozzle as the cleaner is moved back and forth across the floor. To prevent it from passing too far 90 into the nozzle or from interfering with the action of the brush and to insure a proper relation between brush and carpet or floor covering guard fingers are provided. These are preferably fixed at the front edge of the nozzle and extend rearwardly, and in the form here shown they are preferably 95 curved, practically throughout their length and concentric with the brush. They also lie in the path of the ends of the bristles so as preferably to be swept throughout their 100 lengths by such bristles. They are preferably provided with curved ends which also lie in the path of the bristles and are swept by them. These fingers may be of any desired length. They extend across the nozzle 105 in the direction of rotation of the brush and their free ends are therefore within the suction chamber. The fingers being concentric with the brush are obviously upwardly bent away from the casing so as to leave a relatively wide gap between the rear edge of the nozzle and the ends of the fingers. As the machine operates the brush sweeps the fingers 110 preferably from end to end and particularly it sweeps the ends of the fingers. It must be understood that in the operation of such a cleaner it is moved rapidly back and forth over the floor covering and across the edges and fringes thereof, and that there is a strong tendency for the loose loops, thread ends and the like of such floor covering to 115 pass up into the casing. Many of these are in the shape of loops and said loops frequently catch over the ends of the fingers, if the latter are not properly formed, shaped, or protected with the result that 120 125 130

the action of the machine is interfered with and the floor covering is injured. By sweeping the ends of the fingers with the brush it is obvious that the brush may be kept 5 clean, and all such objects are swept by the brush free from the fingers so that they pass on into the suction chamber. The brush is not intended to project far down into the nap of the carpet and the guard fingers prevent the carpet from rising too high, but 10 the brush sweeps up the litter referred to and the fingers tend to prevent such litter from adhering to the brush and proceeding with the brush in its rotative movement. 15 The brush sweeping the fingers prevents the litter in question from adhering to the fingers and thus the co-action of the brush and fingers is carried on effectually each tending to clear the other of the surface 20 litter which it is so necessary to deliver free from the brush and fingers into the suction chamber. As above indicated these several actions are facilitated when the fingers are concentric, when they lie within the path of 25 the bristles, when their free ends at least are in the path of the bristles and preferably curved, and when the brush rotates continuously in the same direction so as to sweep the fingers from their inner fixed toward their free ends. 30

The fingers must be free from the rear lip of the casing nozzle so as to permit the litter in question and match sticks and the like to pass into the suction chamber between the rear lip of the nozzle and the guard fingers. The litter, along with the current of air entering the machine, lies largely or moves to a great extent in a plane which is above the inner surface of the rear 35 lip, that is to say there is a stream of dirt and litter and dust laden air at this point and the fingers preferably extend so as to deliver from their free ends the object which passes along the fingers into such stream. If, however, for any reason, the brush is to be reversible or adapted to rotate alternately in opposite directions, then the inner ends of the fingers should be carried higher up so as to be practically outside 40 of such stream so that in the event of the brush rotating in a direction opposite to the flow of current of air and litter there will be no opportunity for the ends of the fingers to intercept or pick up material in the air stream. Indeed, for some purposes 45 with respect to certain kinds of material, it may be preferable to have the fingers extended well up into the suction chamber and beyond the upper dust and dirt laden stream even in cases where the brush rotates toward the free ends of the fingers. 50

It will be understood that the drawings are intended merely as an illustration of one form of the invention, for the device 55 illustrated and described might be altered 60

and changed considerably without departing from the spirit of my invention. In the preferred form of my invention as it now appears the brush rotates continuously in the same direction at a relatively high speed, and wherein the fingers are concentric throughout the greater portion of their lengths and lie slightly within the brush bristles so that they are swept by the brush, 70 for the fingers protect the brush from the adhesion of the class of surface litter referred to and the brush protects the fingers by sweeping such litter from them into the stream of air. It is important that whatever the shape of the finger, generally speaking, its ends should extend into the bristles and be swept by the brush. 75

Another form of the invention is that wherein the fingers are extended beyond the stream of litter laden air so as to deliver 80 the dust laden air. 85

While I have stated that the brush mounting revolves always in the same direction, in certain circumstances the direction of its rotation might be reversed, and I do not wish to be limited to a construction wherein the brush is driven always in the same direction. 90

I claim:

1. In a suction cleaner, a suction nozzle, a brush rotatably mounted therein, a plurality of guard fingers extending across the open mouth of the nozzle, said fingers being arranged in pairs, each pair being joined together at one side by a part perpendicular to each of them, a supporting member having perforations through which each finger separately passes and means located between such fingers for holding each pair in position. 95

2. A brush guard for suction cleaner nozzles comprising a plurality of U-shaped fingers each separately mounted in the hood and means for permanently fastening each finger in position independent of the others. 100

3. A brush guard for suction cleaner nozzles comprising a plurality of U-shaped fingers each separately mounted in the hood. 110

4. A brush guard for suction cleaner nozzles comprising a plurality of pairs of joined fingers each pair being separately mounted in the hood, means for permanently fastening each pair in position, independent of the other, and means for holding the fingers in place comprising a member engaging the connecting part intermediate the fingers. 115

5. In a suction cleaner a suction nozzle having a plurality of perforations adjacent the open mouth of the nozzle, a plurality of brush guard fingers extending through said perforations and extending across the nozzle, said fingers being arranged in pairs, means for fastening each pair of fingers independently in position, said means com- 120 125 130

- prising a slot, connecting members extending between the two fingers of each pair located within said slot and means for holding said connecting member in the slot.
5. 6. In a suction cleaner, the combination of a casing having an inlet nozzle with a brush mounted adjacent said nozzle, means for rotating the brush at a relatively high speed continuously in the same direction and 10 guard fingers which are fixed at one end and free at the other, and projecting across the nozzle in the direction of the rotation of the brush and concentric throughout the major portion of their lengths with the 15 brush and whose free ends lie in the path of the bristles so as to be swept thereby.
7. In a suction cleaner, the combination of a casing having an inlet nozzle with a brush mounted adjacent said nozzle, means 20 for rotating the brush continuously in the same direction and guard fingers which are fixed at one end and free at the other projecting across the nozzle in the direction of rotation of the brush and concentric 25 throughout the major portion of their lengths with the brush and whose free ends lie in the path of the bristles so as to be swept thereby.
8. In a suction cleaner, the combination 30 of a casing having an inlet nozzle with a brush mounted adjacent said nozzle, means for rotating the brush and guard fingers which are fixed at one end and free at the other projecting transversely of the nozzle in the 35 and concentric throughout the major portion of their lengths with the brush and whose free ends lie in the path of its bristles so as to be swept thereby.
9. In a suction cleaner, the combination 40 of a casing having an inlet nozzle with a brush mounted adjacent said nozzle, means for rotating the brush, and guard fingers
- fixed at one end and free at the other projecting transversely of the nozzle, and whose free ends lie in the path of the brush bristles 45 so as to be swept thereby.
10. In a suction cleaner, the combination of a casing having an inlet nozzle with a brush mounted adjacent said nozzle, means for rotating the brush continuously in the 50 same direction and guard fingers which are fixed at one end and free at the other projecting transversely of the nozzle in the direction of the rotation of the brush and whose free ends lie in the path of the 55 brush bristles so as to be swept thereby.
11. In a suction cleaner, the combination of a casing having an inlet nozzle with a brush mounted adjacent said nozzle, means for rotating the brush continuously in the 60 same direction, and guard fingers which are fixed at one end and free at the other projecting transversely of the nozzle in the direction of the rotation of the brush and having curved free ends which lie in the 65 path of the bristles of the brush so as to be swept thereby.
12. In a suction cleaner, the combination of a casing having an inlet nozzle with a brush mounted adjacent said nozzle, means for rotating the brush continuously in the 70 same direction and guard fingers which are fixed at one end and free at the other projecting transversely of the nozzle in the direction of the rotation of the brush and concentric throughout the major portion of their lengths with the brush and whose free ends lie in the path of its bristles so as to be swept thereby.
- Signed at Chicago county of Cook and 80 State of Illinois, this 23rd day of February, 1921.

HOWARD EARL HOOVER.
